United States Patent Office.

JOSEPH SHACKLETON, OF RAHWAY, NEW JERSEY.

Letters Patent No. 101,669, dated April 5, 1870.

IMPROVEMENT IN STEAM HEATERS.

The Schedule referred to in these Letters Patent and making part of the same

To all whom it may concern:

Be it known that I, JOSEPH SHACKLETON, of Rahway, in the county of Union and State of New Jersey, have invented a certain new and improved Steam-Injector, for utilizing exhaust steam for heating purposes; and I do hereby declare that the following is a full, clear, and complete description of the same, reference being had to the accompanying drawings making part of this specification, in which drawings—

Figure 1 is a side view of the injector for utilizing exhaust steam for heating purposes.

Figure 2 is an end view.

Like letters of reference refer to like parts in the several views.

Objective.

The nature of this invention relates to an arrangement of certain devices by which live steam is employed to facilitate the escape of exhaust or exhausting steam, when used for heating purposes, thereby reducing the back-action on the piston when exhaust steam is utilized for heating purposes, as herein set forth.

Description.

A and B, fig. 1, represent an ordinary steam-boiler and furnace, by the side of which is an engine, C, to which it is connected by an induction steam-pipe, D, and of which E is the exhaust-pipe, all of which is or may be constructed in the ordinary way.

The system or arrangement of pipes for heating purposes is connected with the exhaust-pipe E by any suitable means.

The induction and exhaust-pipes are put in communication with each other by a jet-pipe, F, provided with a key, G, whereby the communication between the pipes may be cut off when so required.

In the use of exhaust steam for heating purposes, the jet-pipe may be connected directly to the boiler, instead of to the induction-pipe.

It occurs in a system or arrangement of pipes for heating, that the action of the condensed and con-

densing steam therein from the engine, prevents a free escape of the exhaust, which produces a back-action on the piston. This is greatly more so when the apparatus used in heating is of large size, and especially is this the case when the extended range of pipes is used. Under such circumstances, the back-pressure on the piston is greatly increased, and therefore is a serious obstruction to the full working capacity of the engine.

To avoid such obstruction is a feature of this invention, and which is effected as follows:

From the induction-pipe D, or directly from the boiler, a fine jet of live steam is conducted into the exhaust-pipe E, which is supposed to be attached to the heating apparatus, by the pipe, F, referred to, the result of which is to drive the steam lingering in the exhaust and connecting-pipes forward by the force and activity of the steam, taken directly from the induction-pipe or boiler, thereby not only facilitating the escape of the exhausting steam, and relieving the engine from back-pressure, but assisting in raising the temperature of the heating apparatus to that degree of heat that little or no condensation of steam will take place in the heater; hence the exhaust-steam will escape without obstruction, and, consequently, the engine will run free of back-pressure.

The live steam may be shut off by means of the stop-cock G referred to, and all the live steam used upon the piston.

Claim.

What I claim as my invention, and desire to secure by Letters Patent, is—

The devices, substantially as herein described, for heating by means of exhaust and live steam, consisting of the pipe F, in combination with pipe D, or boiler, and exhaust-pipe E.

J. SHACKLETON.
